ELECTRIC MULTIPLE OUTLET

Robert S. Pennock, Fayetteville, and Mark N. Russell, Syracuse, N. Y., assignors to Pass & Seymour, Inc., Solvay, N. Y., a corporation of New York

Application July 18, 1938, Serial No. 219,746

3 Claims. (Cl. 173—330)

This invention relates to multiple outlets, for installation in the permanent electric wiring systems of buildings to receive and coat with a like plurality of multi-bladed plugs attached to respective extension-cords or the like.

While multiple outlets very commonly have their fixed contacts along each side integrally connected together so that two wires, respectively connected to the two side-strips of contacts, may serve all of the stations, wiring necessities sometimes make it desirable that each station be a separate one individually served by its own particular pair of wires; and in other instances it is desirable that one side of all of the stations be served by a common, single wire but that on the other side each station shall have its two or more contacts individually isolated and each connected with a separate service-wire.

In commercial practice it is customary for manufacturers to factory-build multiple-outlet devices particularized to each of these three types of wiring which may, for convenience, be called "common supply and return," "separate supply and return" and "common-supply separate-return" types, in the sequence above described.

A general object of the present invention is to provide a novel and advantageous multiple-outlet structure which, as marketed, will be suitable for "common supply and return" type of installation, but which the electrician may very readily and satisfactorily alter, on the job, to serve the needs of either of the other two types of wiring above mentioned; thus to minimize production cost by standardizing on a single structure in lieu of three distinct ones, to lessen the stocks that jobbers and dealers must carry, and to make it unnecessary for the electrician to ascertain in advance the particular type or types of multiple outlets that must be used on a given job.

A further general object of this invention is to provide, in such a multiple-outlet structure, fixed contacts on each side thereof all interconnected electrically in single-piece construction but with the normal, unitary connections between adjoining fixed contacts on each side of the device arranged for and accessible to easy intentional "break off" removal without disassembling any parts of the unit, and with binding-screw provision available for each contact on both sides of the device.

Further objects of the invention are so to construct and combine the elements of the novel structure that it may be of rugged strength, economical of manufacture, easy to assemble,

practically proof against accidental breaking off of any of said normal unitary connections between contacts on the same side, amply safeguarded against electrical hazards such as short-circuiting or "sparking" between broken-apart contacts on the same side, adapted to permit of quick and easy removal of any and all of said break-off connections as by use of ordinary pliers, and with all permanent parts of the structure securely held in proper positions regardless of the presence of or the removal of the "break off" portions.

For attainment of these and other objects which will hereinafter become apparent, the present invention consists in the features of construction and combinations of parts hereinafter set forth and claimed, reference being had to the accompanying drawings wherein we have illustrated, for purposes of full disclosure, a duplex outlet that embodies the invention in a specific construction which has been found to attain the stated desirata very satisfactorily from a practical standpoint.

In the drawings:

Figure 1 is a perspective view of a duplex outlet embodying this invention;

Fig. 2 is an exploded perspective view showing the casing parts, contacts and support-members in position to show details of their construction and facility of their assembly;

Fig. 3 is an enlarged transverse section on line 3—3 of Fig. 1; and

Figs. 4, 5 and 6 are conventionalized diagrams of the several available types of wiring connections aforesaid; being respectively "common supply and return," "common-supply separate-return," and "separate supply and return."

In the embodiment of the invention shown, 10 indicates in general the duplex socket, illustrated in a form particularly designed for "flush" installation in connection with a wall plate (not shown), as is suggested by the "plaster ear" type of mounting straps 11; the two-piece shell or casing 12 of the unit being molded of suitable insulating material and comprising a rather deep body 13 and a complementary shallow base 14 matching it in plan-contour.

These casing members, when assembled, are secured together by a center-rivet 15 tapped as 50 at 16 (Fig. 3) for the customary wall-plate screw and having its squared head 17 engaged in a corresponding socket in said base; relative twisting of the two casings parts about the rivet-stem being prevented by interlocking the end portions 55

of the two shell parts against such relative movement as hereinafter described.

Opposed T-slots 20, 20 in the conventional face-molding of each outlet station will admit 5 the blades of standard types of plugs into contact, within the shell, with the pair of fixed contacts for that station, respectively at opposite sides thereof; and the "waist" 21 between the face-molding of the two contact-stations is conventionally sunk to accommodate the wall plate. 10

Each side-wall of the insulating casing 12 is formed to provide a suitably-shaped recess 22, located between the adjoining contact-stations and preferably extending the full height of the 15 side-wall, to expose the "break off" portions of the appropriate contact-strip and also the wire-receptive binding screws therefor, these parts being sunk a little below the side-plane of the casing but readily accessible; and further, each said 20 recess 22 is desirably bisected by a vertical separator-rib 23, shown as extending full height of the recess, to insulate from each other, and to aid in positioning, contiguous plate-portions of the conductor-unit, from which the plate-connecting "break off" portions may be removed on occasion, as hereinafter more fully described. 25

Each conductor-structure 25 is herein shown as a single-piece strip, formed to provide longitudinally-separated clusters of contact-springs 26 30 to serve respective outlet stations; respective binding-screw plates 27 connected with said contacts and somewhat spaced apart at their adjoining edges; and narrow "break off" straps 28, bridging between the plates at their top and bottom and weakened by grooves 29 at their lines of juncture with the plate-edges.

As shown in Fig. 1, the fixed-contact unit 25, when in place in the shell, has its binding-screw plates 27 largely exposed in the wide bottom-portion 22^a of the shell-wall's recess 22 and the narrower "break off" straps 28 are likewise accessibly exposed but without protrusion beyond the side plane of the shell; the upper one of said straps lying in narrow top-portion 22^b of recess 22, 45 which need only be of convenient width to receive the nose of suitable pliers for breaking off the strap.

In the desirable construction shown, the "break off" straps 28 are of arched or U-shaped 50 conformation, to straddle a separator-rib 23, which is of somewhat greater protrusion than the thickness of the binding-screw plates 27. Desirably, also, the "break off" straps diverge with respect to each other as they leave the plane 55 of the plates, at low angles to the latter, so that they arch over the separator-rib in inclined position; but due, in part, to the weakened lines 29 thereof, they may be easily pried up to vertical relation to the plates so that they may be fully 60 gripped with pliers to be broken off, although their initially low angle substantially obviates accidental breaking off in manufacture and handling.

In marketing the unit, binding screws 32 are 65 provided for all of the plates 27, and it will be apparent that the wiring connections of the several diagrams 4, 5 and 6 may be realized by leaving the "break off" straps intact and utilizing any 70 two binding screws on opposite sides of the device for the two-wire connection of Fig. 4; or "breaking off" the straps 28 on one side only of the device and utilizing three binding screws for the wiring of Fig. 5; or, for the complete separation 75 of circuits through the two outlets, shown in Fig.

6, removing all of the "break off" straps and utilizing all four binding screws.

Under conditions where some or all of the "break off" straps have been removed, as indicated in Figs. 5 and 6, it is especially desirable 5 that the separated binding-screw plates be very securely positioned against moving toward each other and of course safeguarded against hazards of short-circuiting. Also, it is very desirable that both the electrical parts and the casing be suitable for economical production to make their advantages available at low price, and these ends are well attained in the particular construction 10 of the contact elements and the casing as herein shown. 15

Desirably, for these and other purposes, the interior of the casing 12 is divided into four sections by the longitudinal partition 33 and the lateral partition 34, each shown as extending the full depth of the casing; matching portions of 20 such partitions being provided on the base 14 and body 13, respectively. The junction of these partitions at the center of the structure is enlarged into a hollow post 35 through which the assembly 25 rivet 17 passes, and the cross partition 34 merges into the separator-ribs 23 (which in part 25 form its edges), that fit neatly between the plates 27 of the contact strips.

On the base 14, chambers 36 snugly receive the bottom-length of the contact-strips and low 30 cleats 37, extending longitudinally, have their ends arranged to form abutments for the confronting base-walls of the contact-clusters, to prevent longitudinal shifting of the latter toward each other when the "break off" connections 28 between the plates 27 have been removed; while opposite the top portion of each plate 27 the body of the casing 12 has integral 35 bracing-cleats 38, paralleling the side-wall of the casing and reaching down behind said plates. 40

Thus, screw-driver pressures tending to tilt the tops of the plates backward or otherwise displace them are adequately resisted even when the "break off" straps are removed, and the wrenching of the contact strips in removing said 45 straps does not displace the plates 27 or contact-spring clusters 26. The safeguarding of the permanent electrical parts against displacement is furthered, and ease of assembly of parts is promoted, by providing on each binding-screw plate 50 27 top and bottom positioning-lugs, 40 and 41, respectively, to engage receptive notches 40' and 41' molded respectively in body 13 and base 14 of the casing.

For strength of the construction and to interlock the body and base of the casing against 55 relative turning about the center-rivet 15, the "plaster ear" members 11 are formed with a relatively narrow horizontal neck 43 and wider body 44 arranged at right angles thereto, this L-shaped structure being adapted to be slipped into a shallow T-slot 45 extending vertically in the end wall of the shell from the bottom thereof to adjacent its top; the bottom of said metal member 44 extending slightly below the bottom plane of 60 the casing body 13 to engage in a receptive cross-slot 46 in the base 14. Also, the base is provided with an upstanding lug 48 abutting the outer face of metal member 44 and fitting into the narrowed outer-portion of T-slot 45, to augment the strong 65 70 interlock of the parts.

While we have herein described in detail a particular embodiment of our invention that we deem highly advantageous, it will be understood 75 that variations in details of embodiment may be

made without departure from the spirit of our invention, within the scope of the appended claims.

We claim:

5. 1. In an electric wiring device, a body and a base jointly providing a casing having thin side-walls and thick end-walls, said body having outwardly opening T-slots extending from near the top to the bottom of its end-walls and said base
- 10 having openings therein registering with the transverse portions of said T-slots and carrying upstanding lugs fitting the outward openings of said T-slots; two casing-supporting units engageable with said T-slots, each consisting of a metal strap having a wider body-portion fitting the transverse portion of a said T-slot and a narrower supporting-neck, at right angles thereto, fitting the outward opening of said T-slot and protruding at the top thereof, the free end of said
- 15 strap-body extending below said casing-body and projecting into the registering opening in said base; and a single connector centrally uniting the body and base of said casing.
- 20 2. In an electrical wiring device, a body and a base jointly providing a casing having thin side-walls and thick end-walls, said body having outwardly opening T-slots extending from near the top to the bottom of its end-walls and said base having openings therein registering with the transverse portions of said T-slots and carrying upstanding lugs fitting the outward openings of said T-slots; two casing-supporting units engageable with said T-slots, each consisting of a metal strap having a wider body-portion fitting the transverse portion of a said T-slot and having a narrower supporting-neck, at a substantially right angle thereto, fitting the outward
- 25 opening of said T-slot and protruding at the top thereof, the outer face of said strap-body abutting the adjacent upstanding lug carried by said base and the free end of said strap-body extending below said casing-body and projecting into the registering opening in said base; and a single connector centrally uniting the body and base of said casing.
- 30 3. In a multiple-outlet unit, a two-piece insulating casing having in its face blade-openings 10 for a number of plug-stations and in each side-wall a recess located between adjacent plug-stations, each of said recesses containing a vertical separator; two longitudinally extending conductor-structures arranged within said casing 15 adjacent said side-walls, each of said structures comprising a number of longitudinally spaced-apart contacts registering with the corresponding blade-openings of said plug-stations, binding-screw plates permanently connected respectively 20 with said contacts and extending into adjacent ones of said side-wall recesses and on opposite sides of said separator and integral "break-off straps" means disposed substantially entirely in 25 said recesses and spanning said separators and connecting adjacent ones of said plates; means including cooperating pairs of notches formed in the two pieces of said casing and engaging the edges of said plates for anchoring said plates in place independently of the remainder of said 30 structure; means including integral backing cleats carried by the two pieces of said casing for retaining said plates in place upon removal of said break-off connections; and means for securing together the two pieces of said casing. 35
